CLAIM

The ornamental design for a gear panel, as shown and described.

DESCRIPTION

FIG. 1 is a front elevational view of a gear panel showing our new design.

FIG. 2 is a rear elevational view thereof.

FIG. 3 is a left side view thereof.

FIG. 4 is a right side view thereof.

FIG. 5 is a top view thereof.

FIG. 6 is a bottom view thereof.

FIG. 7 is a front bottom right perspective view thereof; and, FIG. 8 is a front top right perspective view thereof.

The broken lines depict a boundary around the de-emphasized elements, which illustrate portions of the gear panel which form no part of the claimed design.
